UNITED STATES PATENT OFFICE.

LUDOVICO GIOMMI, OF MILAN, ITALY.

APPARATUS FOR STERILIZING LIQUIDS CONTAINED IN HERMETICALLY-CLOSED VESSELS.

1,249,740.

Specification of Letters Patent. Patented Dec. 11, 1917.

Application filed April 9, 1913, Serial No. 760,086. Renewed December 22, 1916. Serial No. 133,440.

To all whom it may concern:

Be it known that I, LUDOVICO GIOMMI, a subject of the Italian King, and resident of Milan, Italy, have invented certain new and useful improvements in Apparatus for Sterilizing Liquids Contained in Hermetically-Closed Vessels, of which the following is a specification.

The present invention relates to a new apparatus for sterilizing in a heated room liquids contained in hermetically closed recipients such as bottles.

The most important reasons why bottles break during the sterilizing process are the following ones:

(1.) The difference of pressure inside and outside the bottle when the temperature rises in the room.

(2.) The bottles do not dilate uniformly because of the different thermic conductivity between the liquids and the gases in contact with the liquids.

During the heating process the portion of the bottle in contact with the gas which necessarily remains within the bottle after filling, will become heated more quickly than the portions of the bottle which are in direct contact with the liquid.

(3.) The difference of density of the air layers surrounding the bottle.

The temperature is higher in the upper layers or strata than in the lower ones.

It results from this fact that it happens that all the bottles are not in identical conditions of inner pressure.

The outer, artificial pressure being uniform in the whole of the sterilization chamber, is unable to equilibrate the inner pressure of all the bottles at the same instant.

The present invention is based on the consideration of the above stated reasons and the improvement consists in moving the bottles during the process in order to continuously displace the gas bubbles in the interior of the bottles so as to provide a uniform temperature and pressure at the interior of all the bottles.

The accompanying drawings show one constructive form of the apparatus.

Figure 1 is a longitudinal section of the main apparatus.

Fig. 2 is a side view corresponding to Fig. 1.

Fig. 3 is a transversal section on line *y*—*y* of Fig. 1.

55

Fig. 4 is a section on line *w*—*w* of Fig. 3.

Fig. 5 is a section on line *z*—*z* of Fig. 3.

Fig. 6 is a transverse section of a second accessory part of the apparatus.

Fig. 7 is a partial axial section corresponding to Fig. 6.

Fig. 8 is a perspective view of the second or accessory part of the apparatus.

Figs. 9, 10 and 11 are constructive forms of the heating means of the apparatus.

65

The apparatus is composed of a cylindrical chamber 1 arranged for receiving a plurality of drums 2 which may be introduced at one side of said chamber.

In said drums are arranged the bottles 70 containing the liquids to be sterilized and rotated by means of the device shown in Fig. 8. A removable cover 3 hermetically closes the chamber 1.

Through a cock 4 is introduced the fluid 75 under pressure for balancing the pressure inside the bottles. A manometer 22 indicates the pressure in the chamber 1 while one bottle 6 is provided with a manometer 5 for indicating the pressure within the bottles.

80

The increasing or decreasing of the temperature of the bottles is produced by means of a fluid entering the outer annular space or jacket 7 through a duct provided with a cock 8, and the central space 9, through the 85 pipe 13 provided with a cock 11.

When the cock 11 is opened, the hot fluid or steam enters the tube 13 which is open at its opposed end 14. By means of the cock 12 the condensed steam is withdrawn from space 9. 15 (Fig. 2) is a pipe provided with a cock 17 for providing water during the cooling down. 18 is a cock provided on the pipe 16 for drawing off the water. 19 is the outlet cock of the cooling fluid from 95 jacket 7. 20 and 20' are safety valves; 21 and 22 are manometers.

Fig. 9 is a different constructive form of the heating jacket 7. It is formed by means of a plurality of tubes located within the 100 chamber 1 and connected with each other.

The annular space as well as the tubular chamber 23 may be divided in compartments 24, 25, 26 (Fig. 10) or in rows of tubes 27, 28, 29 (Fig. 11) independent from each other 105 and receiving steam at different tempera-

tures according to their level in order to produce a uniform temperature of the atmosphere surrounding the bottles to be sterilized, without necessity to rotate the latter as it will be described hereinafter.

8² are the steam inlet pipes, 8³ the outlets pipes for the condensed steam.

The rotary apparatus according to Figs. 1, 3 and 4, comprises annular drums 2 provided with rollers 30. The bottles are horizontally disposed within the drum.

Said drums are introduced after each other in the chamber 1 and are put in condition for rotating around a pivot formed by 15 means of a cylindrical frame 32 (Figs. 1, 3, 4, 6, 7, 8) provided with guides 33 for guiding the drums when introduced and with rollers 34 for rotating said drums together with frame 32 on the central tube 9.

20 The apparatus shown in Figs. 6 and 7 serves for supporting the central tube 9 when the apparatus is very long.

The cylindrical frame 32 is provided at one end with a toothed wheel 35 (Figs. 1 25 and 8) engaging a pinion 36 mounted on the shaft bearing the pulley 37 which is actuated by a motor not shown in the drawings.

The device (Figs. 6 and 7) supporting the pivot and consequently the whole rotary device 30 comprises: a circular U shaped guide 38 provided at its outer periphery with rollers 39 for readily introducing the device into chamber 1; a concentrically disposed ring 40 is provided with radial supports 41 on which are mounted rollers 42 rolling on the guide 38 and with inner rollers 43 rolling on the guides 38.

Having now fully described my said invention, what I claim and desire to secure 40 by Letters Patent, is

1. An apparatus for sterilizing in a heated room liquids contained in hermetically closed recipients comprising a horizontally disposed cylindrical heating chamber, a 45 fixed closure at one end of said chamber, a removable closure at the opposite end of said chamber, heating and cooling means at the inner periphery of said chamber, an axially disposed cylindrical heating and cooling device, means for supporting said axial device, means for introducing steam and cooling fluid within said heating and cooling device, means for evacuating the condensed steam and cooling fluid from said 50 devices, a plurality of annular drums located in said chamber between both said heating and cooling devices for receiving the hermetically closed recipients containing the liquid to be sterilized, means for 55 rotating said drums and means for introducing a fluid under pressure into said chamber containing the hermetically closed recipients to be sterilized in order to balance the pressure in the interior of said recipients.

2. An apparatus for sterilizing, in a heated room, liquids contained in hermetically closed recipients comprising a horizontally disposed cylindrical chamber, a fixed closure at one end of said cylindrical chamber, a removable closure at the opposite end of said chamber, an annular heating and cooling jacket at the inner periphery of said chamber, an axially disposed heating and cooling cylinder, means for supporting said cylinder in said chamber, pipes for providing steam and cooling fluid to said peripher 70

al and axial heating and cooling means, pipes for evacuating the condensed steam and cooling fluid from said heating and cooling means, cocks inserted in said pipes for adjusting the flow of steam and of fluid through said pipes, a plurality of annular drums located in said chamber, between both said heating and cooling means, hermetically closed recipients containing the liquid to be sterilized, and horizontally arranged within said drums, grooved pulleys 80

at the smaller cylindrical wall of each of said drums, a plurality of rings loosely surrounding said axial heating and cooling cylinder, and forming the rotating means for 85

said drums, longitudinally disposed bars secured at the outer periphery of said rings and engaging the grooves of said pulleys 90

for guiding said drums when introduced in said chamber, radially disposed rollers on the inner periphery of said rings and bearing on said axial heating and cooling cylinder, guiding bars and rollers forming a 95

rotary frame on which the drums are engaged by means of said grooved pulleys, a toothed wheel secured at one end of said frame, a shaft, a pinion keyed on said shaft and engaging said toothed wheel and a pulley secured on said shaft for rotating said 100

frame together with the drums engaged on said frame by means of said grooved pulleys.

3. An apparatus for sterilizing in a heated chamber liquids contained in hermetically closed recipients comprising a horizontally disposed cylindrical heating chamber, a fixed closure at one end of said cylindrical chamber, a removable closure at the opposite end of said chamber, sets of pipes 110

independent from each other, forming a peripheral heating and cooling jacket in said chamber, means for providing steam and cooling fluid in said jacket, means for withdrawing the condensed steam and cooling fluid, means for controlling the flow of 115

steam and cooling fluid on said sets of pipes, an axially disposed heating and cooling tube in said chamber, means for supporting said tube in said chamber, means for providing 120

the steam and the cooling fluid to said tube, means for adjusting the flow of steam and cooling fluid on said tube, a plurality of annular drums located in said chamber, between both said heating and cooling means, 125

130

hermetically closed recipients containing the liquid to be sterilized, arranged in said drums, grooved pulleys at the smaller cylindrical wall of each of said drums and longitudinally disposed guides engaging the grooves of said pulleys for guiding said drums when introduced into said chamber.

In testimony whereof I have hereunto set my hand in presence of two witnesses.

LUDOVICO GIOMMI.
